US0D1059800S

(12) **United States Design Patent** (10) **Patent No.:** **US D1,059,800 S**
(45) **Date of Patent:** **** Feb. 4, 2025**

(54) **PAIN FREE KNEE CRUTCH**

(71) Applicant: **Jonathan David Neighbors**, Anderson, SC (US)

(72) Inventor: **Jonathan David Neighbors**, Anderson, SC (US)

(**) Term: **15 Years**

(21) Appl. No.: **29/944,885**

(22) Filed: **May 30, 2024**

(51) **LOC (15) Cl.** **03-03**

(52) **U.S. Cl.**

USPC **D3/7**

(58) **Field of Classification Search**

USPC D3/5, 6, 7, 8, 9

CPC A61H 3/02; A61H 3/0288

See application file for complete search history.
